PORTABLE SELF-PROPELLED SCAFFOLD

Hugh F. McClain, Long Beach, Calif.

Application March 23, 1945, Serial No. 584,318

10 Claims. (CL. 304—2)

This invention relates to a portable self-propelled scaffold, the primary object of the invention being to provide a scaffold especially designed for use in dry docks or ship-building yards.

An important object of the invention is to provide a scaffold of this character including a pivoted staging section mounted on a movable support, so that the staging may be tilted and secured in its adjusted tilted positions to move the catwalks carried thereby, in proximity to the ship under repair.

Another important object of the invention is to provide a scaffold including a pivoted section on which the catwalks are adjustable independently of each other and in horizontal planes so that the forward edges of the catwalks may be moved to positions adjacent to the hull of the ship, to the end that the workers standing on the catwalks may have easy access to their work.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

Referring to the drawings

Figure 1 is a side elevational view of a scaffold constructed in accordance with the invention, the pivoted staging section thereof being shown in its adjusted position in dotted lines.

Figure 2 is a rear elevational view of the scaffold.

Figure 3 is a sectional view taken on line 3—3 of Fig. 2.

Figure 4 is a sectional view taken on line 4—4 of Fig. 3.

Figure 5 is a sectional view taken on line 5—5 of Fig. 1.

Figure 6 is a sectional view taken on line 6—6 of Fig. 2.

Figure 7 is a sectional view taken on line 7—7 of Fig. 6.

Figure 8 is a sectional view taken on line 8—8 of Fig. 6.

Figure 9 is a sectional view taken on line 9—9 of Fig. 3.

Figure 10 is a sectional view taken on line 10—10 of Fig. 1.

Figure 11 is a sectional view taken on line 11—11 of Fig. 2.

Figure 12 is a sectional view taken on line 12—12 of Fig. 6.

Figure 13 is an enlarged elevational view illustrating one of the brakes.

Figure 14 is a sectional view taken on line 14—14 of Fig. 1.

Referring to the drawings in detail, the scaffold embodies a rectangular frame comprising front and rear channel bars 5 and end bars 6, the bars 5 and 6 being welded together at their ends providing an exceptionally rigid structure.

This frame provides the chassis for the supporting truck, and has mounted at its forward side, caster rollers 1'.

At the rear corners of the frame, are tubular bearing members 7 disposed vertically, and secured to the bar 5 at the rear of the frame, and the rear ends of the end bars 6, by means of the angle plates 8, which are welded to the rear bar 10 5 and end bars 6. The lower ends of the tubular bearing members 7 are enlarged and formed with annular grooves to receive the ball bearings 9.

The reference character 10 indicates the forks for the traction wheels of the truck or carriage, 20 the forks 10 having openings to receive the axles 11 on which the tubular bearings 12 are mounted.

The tubular bearings are secured within the hubs of the wheels 13 to move therewith. Bevelled pinions 14 are secured to the bearings 12, and are in mesh with the pinions 15 secured to the lower ends of the shaft 16. The shaft 16 is mounted in the bearings 17 and 18, the bearings 17 being secured to the forks 10, while the bearings 18 extend inwardly from the tubular shafts 19 that extend upwardly from the forks 10. In the construction of the forks 10, disk-like bearings 20 are provided, which bearings are also formed with grooves to receive the ball bearings 9.

At the upper ends of the tubular shafts 19, are ring gears 21 that are in mesh with the worms 22 secured at the ends of the shaft 23.

The upper ends of the tubular shafts 19 are closed by the disks 24 which disks provide supports for the bearing arms 25 which depend therefrom.

The shafts 26 extend through the disks 24 and have their lower ends disposed within bearing openings formed in the bearing arms 25. The bearing arms 25 are spaced from the disks 24, providing clearances for the gears 27 that in turn mesh with the gears 28 secured to the shaft 16. Mounted on the upper ends of the shafts 26 are substantially large pinions 29 that

mesh with the pinions 30 secured to the ends of the power shafts 31 which are mounted in the bearings 32 that are secured to the tubular bearing members 7. Differential gearing of the usual and well known construction, is provided in the gear housing 33 and includes a gear mounted on one end of the shaft 34 which carries the beveled gear 35 at one end thereof.

Secured to each shaft 31 at a point adjacent to the differential gearing housing 33, is a brake drum 35' and a brake band 36, the brake bands being operated to grip the brake drums to hold either of the shafts 31 against movement in guiding the scaffold.

Brake-operating levers 37 connect with the brake bands and provide means for operating the brake bands. These brake-operating levers 37 are connected with the pedals 38 for operation by the operator of the scaffold.

A platform 39 forms a part of the truck and extends between the end bars of the frame of the truck. The platform provides a support for the power plant which in the present showing is in the form of a motor 40 which transmits movement to the shaft 41 through the belt 42 operating over the pulley 43 mounted on the end of the motor shaft, and the substantially large pulley 44 secured to the shaft 41. Spaced pinions 45 and 46 are loosely mounted on the shaft 41, the pinion 46 being held spaced from the pinion 47, by means of the bearing 48. The pinion 47 is in mesh with the gear 35 to direct motion to the shaft 34 in operating the shaft 31, through the differential gearing.

Also mounted on the shaft 41 and being in mesh with the gear 35, is a pinion 48'. Pinion 49 is also loosely mounted on the shaft 41, the pinion 49 being in mesh with the gear 50 which in turn is in mesh with the pinion 51 which is loosely mounted on the shaft 41. Gear 50 is mounted on one end of the shaft 52 which carries the worm gear 53 at its free end, the worm gear 53 being in mesh with the gear 54 secured to the shaft 23.

Disposed between the pinions 45 and 46, are clutch members 55 and 56, which are operated by means of the clutch lever 57, to connect either of the pinions 45 or 46, to the shaft 41.

Clutch members 58 and 59 are also connected with the shaft 41 and are adapted to be moved into engagement with the pinions 47 or 48', to connect them to the shaft 41. These clutch members 58 and 59 are operated by means of the clutch lever 60. Clutch members 61 and 62 operated by means of the clutch lever 63, operate between the pinions 49 and 51 and are adapted to connect either pinion to the shaft 41 to operate the gear 50 and shaft 52 either in a clockwise direction or an anticlockwise direction, to guide the truck.

Rising from the truck, and being rigidly connected therewith, is a supporting frame for the movable tower section of the scaffold, which comprises rear bars 64 and 65, and front bars 66, the bars 64 and 65 being connected with the front bars 66 by means of the horizontal bars 67, the main or rear bars of the vertical frame being connected by means of the transverse bar 68.

Bearings 69 are secured to the rear bars 64 and provide supports for the shaft 70 that also extends through the bearings 71 secured to the rectangular frame 72 that is secured to the rear bars. The ends of the shaft 70 are mounted in bearings 73 that are secured at the ends of the

frame 72. The shaft 74 carries the pinion 75 at its lower end, the pinion 75 being in mesh with the pinions 45 and 46 so that rotary movement may be directed from the shaft 41 to the shaft 74 in a direction either to the right or left, for purposes to be hereinafter more fully described.

As clearly shown by Fig. 2 of the drawings, the shaft 74 extends to a point adjacent to the gear 76 mounted on the shaft 70, the shaft 74 carrying the worm 77 which is in mesh with the gear 76 to rotate the gear and shaft 70. Beveled gears 78 are mounted on the shaft 70, and these beveled gears mesh with the pinions 79 that are secured to the rear ends of the screws 80 that move through the threaded members 81, which are provided with shanks 82 that extend through openings in the vertical rear bars of the adjustable tower, forming a part of the scaffold. The connection between the members 81 and rear bars of the tower is such that the members 81 may pivot with respect to the tower. The threaded members 80, as shown by Fig. 11, also move through tubular bearings 83 which are pivotally mounted on the shaft 70 of the stationary upright frame. By operating the clutch lever 57, it is possible to rotate the threaded members or screws 80 to move the tower to its adjusted position, or return the tower to a position adjacent to the stationary supporting frame of which the bars 64 and 65 form a part.

The adjustable tower embodies front and rear bars 84 and 85 respectively, which are connected by the channel bars 86 by means of bolts 86', the channel bars 86 being of lengths to extend appreciable distances beyond the front bars 84, as clearly shown by Fig. 1 of the drawings. These channel bars 86 are arranged in predetermined spaced relation with respect to each other and are pivotally connected with the bars 84 by means of bolts 84' while the rear ends of the bars 86 are connected with the bars 85 by the bolts 87, so that the tower may swing from the vertical position shown in full lines in Fig. 1 of the drawings, to the inclined position as shown in dotted lines in Fig. 1 of the drawings.

The swinging tower is pivotally connected to the stationary supporting frame, by means of the bolts 84' and 87, the latter bolts being shown as extended through the bars 64 and 65 of the supporting frame and bars 85 of the tower. Angular base bars 88' connect the rear bars 85 to brace them against movement with respect to each other. The free edges of the channel bars 86 are turned inwardly, providing tracks 89, as shown by Fig. 8. Secured to the channel members 86 and disposed within the confines of the flanges thereof, are pulleys 90 over which the cables 91 operate.

The catwalks indicated by the reference character 92 embody flooring boards 93 that are bolted to the angle bars 94 by means of the bolts 95, which are shown as passing through openings in the flooring, and through aligning openings in the angle bars 94. The openings in the flooring at one end of each catwalk, are elongated as shown at 96, to the end that the flooring may be adjusted from the full line position as shown by Fig. 10 of the drawings, to the dotted line position, wherein the outer edges of the catwalks may be moved to positions to conform to the general contour of the hull of a ship with which the scaffold is being used.

The angle bars 94 provide supports for the grooved supporting wheels 97 which are mounted on the shafts 98 that extend through the angle

bars 94 and are secured thereto by means of the nuts 99. The grooved supporting wheels 87 operate over the tracks 89, as shown by Fig. 7 of the drawings.

Supported by the angle bars 94 and movable therewith, are pairs of brake arms 100 that are pivotally mounted on the bolts 101 that are shown as extended through the housing 102. Springs 103 connect the brake arms of opposite pairs, as shown by Fig. 6 of the drawings. These brake arms 100, are relatively long so that when they are moved in one direction, they will set up a binding action with the tracks 89. The ends of the arms 100 are forked, so that they fit over the tracks.

Mounted for sliding movement on the housing 102, is a plate 104 that has inwardly turned parallel flanges 105 which are so positioned that when the plate 104 is moved longitudinally of the housing, the ends of the flanges will engage the brake arms 100 to force the arms forwardly out of contact with the tracks. The arms at the opposite end of the housing will trail, allowing the catwalks to be adjusted with respect to the tower, so that predetermined catwalks may be moved outwardly to contact with the hull of the ship with which the scaffold is being used, so that the operators may work in close proximity to the hull of the ship. The cables 91 which connect with the plate 104, move over the pulleys 90, and extend to positions wherein the operators may have easy access thereto to accomplish the adjustment of the catwalk as described. It will be seen that under normal conditions, the springs 103 will operate to cause the free ends of the brake arms to frictionally engage the tracks 89, securing the catwalks in their positions of adjustment. When it is desired to move the catwalks in the opposite direction, the cable 91 at the opposite end of the plate 104 will be operated to move the brake arms at this end of the plate, out of contact with the tracks, whereupon the catwalks may be moved in the opposite direction, the brake arms at the opposite end of the plate, trailing during this movement.

In the operation of the device, the motor 40 is set in motion directing rotary movement to the shaft 41. The clutch lever 60 is now operated to clutch either the pinions 47 or 48 to the shaft, whereupon rotary movement is directed to the gear 35. The shaft 34 is now operated to direct rotary movement to the shaft 31 through the differential gearing within the gear housing 33. The shaft 31 operates the shaft 16, through the gearing shown by Fig. 9 of the drawings, and these shafts 16 rotate the wheels 13, through the beveled pinions 14 and pinions 15.

When it is desired to turn the truck in moving the truck to its proper position with respect to the ship's hull, the clutch lever 63 is operated to rotate the shaft 23 which in turn rotates the forks 10 in which the wheels 13 are mounted. The desired brake pedal is now operated to lock one of the shafts 31 while the other shaft rotates the wheel at the opposite end of the truck, after the truck has been moved to a position adjacent to the hull of the ship, the clutch lever 57 being operated to rotate the shaft 74 and screw 80 to move the tower to the desired position. In order to adjust the catwalks so that they will move to positions to conform with the contour of the hull of the ship, the cables 91 are operated in a manner as previously described to move the catwalks independently of each other. The catwalks will

now be securely held in their positions of adjustment, by the brake arms.

It might be further stated that the gearing and bearings will be encased in a suitable gear housing, not shown, to protect the gearing and bearings against damage by foreign matter such as sand from sand blasters or the like.

In view of the foregoing detailed description, it is believed that a further detailed description as to the operation of the device is unnecessary.

What is claimed is:

1. A scaffold embodying a truck, a vertical supporting frame mounted on the truck, a tower pivotally mounted at the upper end of the supporting frame, a plurality of vertically spaced catwalks mounted on the tower and extending forwardly therefrom, and an adjusting means for moving the catwalks in horizontal planes at right angles to the tower, independently of each other.

2. A scaffold embodying a truck, a vertical supporting frame mounted on the truck, a tower, means for mounting the tower for swinging movement on the supporting frame, adjusting screws adapted to swing the tower on the supporting frame, said adjusting screws adapted to also hold the tower in its positions of adjustment, superposed catwalks mounted on the tower and adapted to extend beyond the front edge of the tower, and means for adjusting the catwalks at right angles to the tower and in horizontal planes towards or away from the tower independently of each other.

3. A scaffold embodying a truck, a support rising from the truck, a tower mounted for vertical swinging movement on the support, adjusting screws adapted to move the tower to various angular positions with respect to the support, catwalks mounted on the tower and arranged in vertical spaced relation with respect to each other, and means for adjusting the catwalks in a line at right angles to the tower and with respect to each other in horizontal planes.

4. A scaffold embodying a truck, a support mounted on the truck, a tower pivotally mounted on the support and being extended an appreciable distance above the support, catwalks mounted on the tower in vertical spaced relation with respect to each other, and means for moving the catwalks in horizontal planes independently of each other in a line at right angles to the tower.

5. A scaffold embodying a base, a support mounted on the base, a tower pivotally connected to the support at a point intermediate the ends of the tower, channel bars providing tracks, secured to the tower, catwalks, said catwalks including rollers movable over the tracks, whereby said catwalks may be extended beyond the front of the tower independently of each other, pairs of brake arms mounted on each catwalk, said brake arms adapted to normally prevent movement of the catwalks by frictional contact with said tracks, operating cables, means operated by the cables for moving predetermined brake arms out of contact with the track, whereby said catwalks are extended beyond the front of the tower, independently of each other.

6. A scaffold embodying a base, a tower mounted on the base for vertical swinging movement, movable catwalks supported on the tower and being disposed beyond the front of the tower, and means for advancing the catwalks in horizontal planes at right angles to the tower, towards and away from the tower independently of each other beyond the normal retracted positions of the catwalks.

7. A scaffold comprising a base, a tower pivotally mounted on the base and embodying vertical bars, channel bars pivotally connected with said vertical bars, said channel bars having their open sides disposed inwardly, providing tracks, said channel bars being extended forwardly beyond the tower, catwalks mounted on the extended ends of the channel bars of the tower and being disposed in vertical spaced relation with respect to each other, rollers mounted on the catwalks and operating over the tracks whereby said catwalks may be extended beyond the forward ends of the channel members, independently of each other.

8. A scaffold comprising a support, a tower pivotally mounted on the support, threaded pivoted bearings mounted on the tower, threaded members mounted on the support and being movable through the threaded bearings whereby said tower may be swung to various angular positions with respect to the support, and a plurality of catwalks arranged in vertical spaced relation with each other on the tower.

9. A device of the character described, comprising a tower embodying vertical bars, chan-

nel bars pivotally connected to the vertical bars, said channel bars having their open sides disposed inwardly providing tracks, movable catwalks including angle bars, rollers mounted on the angle bars, said rollers operating over the tracks, pairs of pivotally connected inclined brake arms mounted on each catwalk, said brake arms having forked ends adapted to straddle said tracks, frictionally engaging the tracks and normally securing the catwalks against movement, means for moving the catwalks along the tracks, said moving means adapted to disengage certain of said arms and tracks.

10. A device of the character described, comprising a tower, horizontal tracks mounted on the tower, catwalks movable over the tracks, pairs of pivoted brake arms mounted on the catwalks, means for urging said brake arms into frictional contact with the tracks, normally securing said catwalks against movement, means for moving the catwalks along the tracks, and said catwalk-moving means adapted to release said brake arms.

HUGH F. MCCLAIN.
